(57) **CLAIM**

The ornamental design for chair having cantilevered seat, as shown and described.

DESCRIPTION

FIG. 1 is a perspective view of my new invention;
FIG. 2 is a left side view thereof, a right side view being a mirror image thereof;
FIG. 3 is a front view thereof;
FIG. 4 is a rear view thereof;
FIG. 5 is a top view thereof; and,
FIG. 6 is a bottom view thereof.

The portions of the chair shown in broken lines form no part of the claimed design.
